(57) **CLAIM**

The ornamental design for a bearing housing, as shown and described.

DESCRIPTION

FIG. 1. is a perspective view showing the bearing housing, obliquely from above, from the right hand side and from the front thereof;

FIG. 2. is a planar view showing the bearing housing in a front view;

FIG. 3. is a planar view showing the bearing housing in a rear side view;

FIG. 4. is a planar top view of the bearing housing;

FIG. 5. is a left hand side view of the bearing housing;

FIG. 6. is a right hand side view of the bearing housing; and,

FIG. 7. is a bottom view of the bearing housing.
